UNITED STATES PATENT OFFICE.

JULIUS STIENEN, OF NEW YORK, N. Y., ASSIGNOR TO FANNY STIENEN,
OF SAME PLACE.

COMBINATION SOFA AND CONVERSATION-CHAIR.

SPECIFICATION forming part of Letters Patent No. 443,301, dated December 23, 1890.

Application filed March 12, 1890. Serial No. 343,616. (No model.)

To all whom it may concern:

Be it known that I, JULIUS STIENEN, of the city, county, and State of New York, a citizen of the United States, have invented certain 5 new and useful Improvements in a Combination Sofa and Conversation-Chair, of which the following is a specification.

This invention has reference to a combined sofa and conversation-chair which can be 10 readily changed from a sofa to a conversation-chair and back again to a sofa; and the invention consists of a combined sofa and conversation-chair composed of a supporting-frame and two independent seats having 15 backs, one seat being centrally pivoted to the supporting-frame while the other seat is guided laterally in ways of the same and connected with the axially-turning seat by a suitable mechanism, so as to impart by the turning of the pivoted seat a reciprocating motion 20 to the sliding seat and permit thereby the change from a sofa to a conversation-chair, and vice versa.

In the accompanying drawings, Figures 1 25 and 2 represent perspective views of my improved combined sofa and conversation-chair, showing the same respectively in position as a sofa and as a conversation-chair. Figs. 3 and 5 show plan views of the seat-frames, corresponding to the positions of the seats shown 30 in Figs. 1 and 2. Fig. 4 is a plan view showing the seat-frames in the act of being moved from one position into the other, and Fig. 6 is a vertical longitudinal section on the line 33, Fig. 3.

Similar letters of reference indicate corresponding parts.

Referring to the drawings, A represents the supporting-frame of my improved combination sofa and conversation-chair. On the supporting-frame A are arranged two seats B B', which are provided with fixed backs C and C'. The frame b of the seat B is pivoted to 45 A, so as to be capable of turning axially on the pivot a'. The frame b' of the seat B' is guided by lugs d' in suitable ways d d of the supporting-frame A, so that it may be moved longitudinally on the same.

The frame b of the seat B is connected by 50 a pivot-rod D with a center pivot e of the frame b' of the seat B', said connecting-rod being pivoted eccentrically to the frame of the seat B, as shown in Figs. 3 and 5, so that when the seat B is turned on its axis the seat 55 B' is reciprocated on its guideways, as shown in Fig. 4, and thereby a sufficient space provided for permitting the turning of the seat B on its axis until its back arrives at the opposite side of the supporting-frame A. As the 60 back approaches this position the connecting-rod D moves the seat B' back again into its normal position until it arrives finally alongside of the seat B, so as to form a so-called "conversation-chair," as shown clearly in 65 Fig. 5.

In place of the connecting-rod D, extending from one seat-frame to the other, any other equivalent mechanism by which reciprocating motion is imparted to the sliding chair 70 may be used.

By returning the seat B back into its original position the conversation-chair is changed back into a sofa.

During the axial motion of the seat B the 75 seat B' is moved away from the seat B, so as not to interfere with the turning of the same, and finally returned again into position alongside of the seat B, so that there is no interference between the seats when the change 80 of position from the sofa to the chair, and vice versa, is made, and thereby a simple and convenient conversation-chair and sofa obtained.

Having thus described my invention, I claim 85 as new and desire to secure by Letters Patent—

1. The combination, with a supporting-frame, of two seats having fixed backs, one seat being centrally pivoted to the supporting-frame, so as to turn on its axis thereon, while the other seat is reciprocated in ways of the supporting-frame, and mechanism for connecting the frames of the seats, so that on turning one seat on its axis the other seat is 90 moved out of the way of the axially-turning seat and returned to its former position side- 95 wise of the same, substantially as set forth.

2. The combination, with a supporting-frame having a transverse brace near the end and longitudinal guideways at the other end, of two seats having fixed backs, one seat being centrally pivoted to the transverse brace, while the other seat is guided in said ways, and a connecting-rod that is pivoted centrally to the frame of the reciprocating seat and eccentrically to the axially-turning seat, substantially as set forth.

In testimony that I claim the foregoing as my invention I have signed my name in presence of two subscribing witnesses.

JULIUS STIENEN.
